ATTORNEYS

UNITED STATES PATENT OFFICE.

RUDOLPH D. BECKER, OF NEW YORK, N. Y.

DRAWING INSTRUMENT.

1,411,151.

Specification of Letters Patent. Patented Mar. 28, 1922.

Application filed December 16, 1919, Serial No. 345,376. Renewed November 17, 1921. Serial No. 515,975.

To all whom it may concern:

Be it known that I, RUDOLPH D. BECKER, a citizen of the United States, and a resident of the city of New York, borough of Manhattan, in the county and State of New York, have invented a new and Improved Drawing Instrument, of which the following is a full, clear, and exact description.

This invention relates to drawing instruments, and has for an object to provide an improved construction of means used in drawing ovals either with a pen or pencil.

Another object of the invention is to provide an instrument for guiding a pen or pencil in drawing an oval which may be adjusted to produce any form of oval desired.

A further object, more specifically, is the provision of a deformable member and means for deforming the same and then holding the member in its set position while the scribing instrument is guided thereby.

In the accompanying drawing:

Figure 1 is a perspective view of an instrument disclosing an embodiment of the invention.

Figure 2 is a longitudinal horizontal section through the structure shown in Figure 1.

Figure 3 is a longitudinal vertical section through Figure 2 on line 3—3.

Figure 4 is a view similar to Figure 3 except the parts are shown collapsed or assembled.

Referring to the accompanying drawing by numerals, 1 indicates a combined casing and frame having a slot 2 through which the fingers may extend when operating the device, and if desired through which the adjusting wheel 3 projects. This adjusting wheel is screwed on to a threaded extension 4 of a measuring or setting slide 5 which extends loosely through an enclosure 6 extending from the sliding plate 7. This sliding plate extends from one edge to the other of the casing 1 and is adapted to slide from one end of the casing to the other.

It will be observed plate 7 is formed with sections 8 and 9, said sections extending from the enclosure 6 to the opposite edges of the casing whereby the ends of the resilient rule or guide 10 may slidably fit thereover as the end of the rule 10 is provided with apertures. The guide or rule 10 is made preferably from some resilient metal, as for instance steel, and is provided

with graduations 11 of any desired kind, and also with a number of apertures 12 at the front end for permitting the proper bowing or flexing when a comparatively small oval is to be provided. The slide 5 has the forward end 13 extending through the guide 10 at the center to which it is riveted or otherwise rigidly secured so that as the slide moves the guide 10 will also move. By moving the slide back and forth longitudinally the axis of the oval may be determined. In order to vary or regulate the width of the oval the retaining plate 14 is provided having extensions at each end through which rivets or other pivotal securing means are passed so that the plate 14 may freely swing within certain limits. When the parts are in the position shown in Figures 1 and 2 and it is desired to provide a wider oval plate 14 is swung upwardly until the same is disengaged from the guide 10 and then the guide manually moved laterally to a point opposite the desired slot 16, after which the plate 14 is again moved downwardly to its lowered position. It will be noted that the plate 14 is provided with a number of slots 16 for holding the guide 10 in the desired position. It will also be noted that a set of graduations 17 is arranged on the upper face of the plate 14 so that each side of the guide will be bowed to the same extent. As shown in the drawing the sides of the guide are bowed so as to be one inch from the center of the slide 5, while the end 18 of the guide is two inches from the plate 14. This arrangement provides for half of an oval and when said half has been applied to an article the entire instrument is reversed so as to make the other half of the oval. This will result in providing an oval two inches wide and four inches long.

Ordinarily the guide 10 and the slide 5 are grasped when the end 18 and the parts are slid back and forth until the desired size is secured, but if a fine adjustment is desired the wheel 3 is moved properly.

When in use the parts are assembled or collapsed to the position shown in Figure 4, wherein the frame 1 acts as a casing for the slide 5, guide 10 and associate parts. If it should be desired to use the device when in the position shown in Figure 4 the plate 14 is first raised or thrown back and the guide 10 and slide 5 grasped near point 18 and these members moved to approximately the position desired for securing the desired

sized oval, plate 14 is then lowered and the sides of the guide 10 are inserted in the desired slots 16, after which the parts are moved back and forth as circumstances demand for securing a better adjustment. A fine adjustment is secured by rotating wheel 3. The device is then placed upon a construction line with the pointer 19 touching the line and the line extending longitudinally beneath the slot 20 in slide 5. A pencil or pen is then placed against the guide 10 and the desired mark produced. In order that an accurate oval may be secured the bottom 1' of casing 1 is cut away at 21 so that the pencil or pen may extend slightly beneath the plate 14 in making the first half of the oval, which will be, as a matter of fact, slightly more than half an oval, the instrument is then turned around and the other half of the oval then produced. If desired one or any desired number of spurs 22 may be connected to the bottom 1' for preventing any accidental slipping of the instrument when scribing a line.

25 What I claim is:

1. An instrument of the character described comprising a resilient strip acting as a guide, means for flexing said strip to produce any sized and any shaped oval, and a casing carrying said means and adapted to receive said strip when not in use.
2. An instrument of the character described comprising a casing, a pivotally mounted slotted plate at the front of the casing, a bowed strip adapted to move in and out of the casing through certain of the slots in said plate, a guiding member in said casing positioned adjacent said slotted plate, said guiding member being formed with a slot, a slide loosely extending through said guiding member and rigidly secured to said strip centrally thereof, and means for adjusting said slide.
3. An instrument of the character described comprising a casing, a guiding

transverse bar arranged in the casing, a strip of flexible material having openings at the ends whereby said ends may slide over said bar, a pivotally mounted plate arranged at the end of the casing formed L-shaped in 50 cross section having slots in one leg of the L adapted to accommodate said strip so as to space the sides of the strip an equal distance from a central line, and a sliding member arranged centrally of the casing and 55 rigidly secured to said strip centrally thereof, said slide and said plate being formed with graduations.

4. An instrument of the character described comprising a casing, a resilient member for forming half an oval, a slide longer than it is wide, having a longitudinally arranged slot, said slide being connected with the center of said resilient member for varying the contour thereof, a pointer connected 60 with said casing opposite the center of said slot, and means carried by the casing for locking the side portions of the resilient member when formed into proper shape.

5. An instrument of the character described comprising a looped member producing half an oval, said looped member being resilient, a casing, a pivotally mounted plate having a number of slots therein adapted to accommodate the side portions 75 or said looped member, a guiding bar arranged in the casing for guiding the inner ends of said looped member, said bar having an enclosure, a slide secured to the center of said looped member formed with a threaded 80 section at the end opposite that secured to the looped member, said threaded section projecting into said enclosure, and a nut positioned on the threaded section and arranged in said enclosure whereby when the nut is 85 rotated said slide will be adjusted longitudinally for varying the curvature of the looped member.

RUDOLPH D. BECKER.
